UNITED STATES PATENT OFFICE.

ALEXANDER M. BELLONY, OF THE UNITED STATES ARMY.

TRUCK.

1,392,103.

Specification of Letters Patent. Patented Sept. 27, 1921.

Application filed May 7, 1919. Serial No. 295,467.

(FILED UNDER THE ACT OF MARCH 3, 1883, 22 STAT. L. 625.)

To all whom it may concern:

Be it known that I, ALEXANDER M. BELLONY, captain, Corps of Engineers, United States Army, a citizen of the United States, stationed at Washington, District of Columbia, have invented an Improvement in Trucks, of which the following is a specification.

The invention described herein may be used by the Government, or any of its officers or employees in prosecution of work for the Government, or by any other person in the United States, without payment of any royalty thereon.

One of the objects of my invention is to provide a truck which, while light in weight, shall be of great strength and durability in use, and which possesses extreme simplicity of construction.

Another object is to provide a truck, of the character noted, embodying an axle-boxing that may be easily separated to permit removal of the axle therefrom.

With these objects in view, the invention resides, broadly stated, in two metallic rings, one of which is carried by the vehicle frame and the second of which is carried by metallic ring-supports, comprising bars each having a base portion which is secured to the axle-boxing and which is bent to provide diverging, upward extending arms, which are secured to said second ring.

The invention also resides in the combination, with the rings, of metallic cross bars carried by each of the rings and through which the king-pin or bolt passes, and in horizontal cross braces secured to the arms of said ring supports.

The invention also resides in an axle-boxing comprising two angle bars carrying removable bolts disposed beneath the axle, whereby, upon removing the bolts, the axle is free to be removed from the boxing.

The invention will be more clearly understood by reference to the accompanying drawing in which like reference characters designate corresponding parts throughout the several views and the several figures of which may be briefly described as follows:—

Referring now in detail to the drawings and first to Figures 1 to 5 thereof, showing a truck adapted for use at the front end of the vehicle: Fig. 1 is a fragmentary top plan

of the forward portion of the vehicle including the upper bearing ring: Fig. 2 is a detailed top plan, of the lower bearing rings, the support, an axle housing and axle: Fig. 3 is a fragmentary sectionized side elevation of the forward truck as assembled: Fig. 4 is a front elevation of the forward truck as assembled: Fig. 5 is a fragmentary detailed perspective view of the ring support: Fig. 6 is a top plan of the rear truck support, the rearward portion of the vehicle and accompanying parts being shown in dotted outline: Fig. 7 is a rear elevation of the rear truck showing parts in assembled relation with respect to the rearward portion of the vehicle: Fig. 8 is a fragmentary detail of the assembly shown in Fig. 7.

1 and 2 designate upper and lower bearing rings, respectively.

Secured to the upper ring 1 are diametric cross braces 3, 3 perforated at their point of intersection, as shown at 4.

To this upper ring the forward portion of the vehicle frame may be secured in any suitable manner. A designates the forward, longitudinally-curved channel bar of the vehicle frame and B, B the longitudinal channel bars of said frame. In this instance, the means for securing the ring to these frame members consists of a pair of channel bars C, C secured at one end thereof to the channel A and the other end to a channel bar D secured in turn to the frame members B, B. The channels C, C and D are secured to the ring, preferably by riveting as shown. An additional channel E, may be secured to the channels C, C and to the ring, preferably by riveting, as shown. Preferably, also, brackets F, F are secured to the channels C, C and to one of the cross-bars 3 and the ring 1. If desired, a bracket G may be secured to the channel D and to one of the cross-bars 3, and another bracket H may be secured to the channel E, to the ring 1, and to the frame channel A, preferably by riveting.

It will be noted that, by the construction described, the ring 1 is very firmly secured to the vehicle frame, and that said construction is exceedingly simple. Secured, as by riveting, to the lower ring 2, are diametric cross-bars 5, 5 provided, at their point of intersection, with registering apertures 6,

registering with the apertures in the cross-bars carried by the ring 1, and through which the king-pin passes.

Secured, as by riveting, to the ring 2, are 5 ring supports crossing each other at right angles, and each comprising a base portion 7, bent to provide upwardly-extending, diverging arms 8, 8 secured to the ring, as by riveting. The base portion 7 of one of the ring 10 supports is secured, as by riveting, to the angle bars 9, 9, constituting the axle-boxing, and the base 7 of the other ring-support is secured, as by riveting, to metallic straps 10 extending transversely to the axle-boxing 15 and secured thereto, as by riveting.

Preferably, a metallic brace 11 is secured, as by riveting, to each pair of arms 8, 8, the two braces thus intersecting or crossing each other and being provided at such point 20 of intersection with registering apertures 12 through which the king-bolt or pin passes.

Additional ring-supports 13, 13 similar in shape to those already described may extend transversely of the axle-boxing 9, 9, and be 25 secured to the ring 2, and each of these ring-supports may be provided with a brace 14.

The axle-boxing comprises two angle bars 9, 9 disposed in parallel relationship and spaced so as to permit of the reception there-between of the axle J, which is advantageously rectangular in cross-section and provided with the reduced extremities j, j. The axle carries collars j', j' abutting the ends of the axle-boxing. Bolts 15 pass 35 transversely through the depending flanges of the axle-boxing, beneath the axle and carry, at their ends, nuts 16. It will thus be noted that, by removing the bolts, the axle is free to be removed from the boxing.

40 The axle-boxing may carry a tongue con-

nection 17, comprising a generally U-shaped member.

Referring, now, to the construction of truck shown in Figs. 6 to 8, adapted for use at the rear of the vehicle. So far as the 45 axle-boxing is concerned, it embodies the same construction as is embodied in the truck shown in the preceding figures of the drawings, and, therefore, need not be specifically described.

Disposed at the top of the axle-boxing, at each end thereof, and secured thereto in any suitable manner, are pedestals 19, preferably comprising two angle bars disposed side by side and secured together, as by riveting 50 19.

Also disposed on top of the axle-boxing and secured thereto, as by riveting, is a cross-bar, comprising a base portion 21, bent to provide two diverging, upwardly-extending arms 22, 22, the bent terminals 23 of 60 which are suitably secured to the pedestals 19, 19. Connecting the arms 22, 22 of the cross brace, is a cross-tie 24 suitably secured at its ends to the terminals 23, 23 and to 65 the pedestals 19, 19, as by riveting.

Having thus fully described my invention, what I claim as new and desire to secure by Letters Patent, is:—

In a vehicle truck the combination with an 70 axle boxing including two elongated members between which an axle is disposable; of a bearing ring, a support for such ring mounted on the axle housing and embodying a trio of inverted V-shaped brackets one 75 of the latter being located in a plane at right angles to the other two and a plurality of intersectioning cross bars interconnecting the free extremities of the several brackets.

ALEXANDER M. BELLONY.
